UNITED STATES PATENT OFFICE.

CHARLES J. BERTHEL, OF CANTON, OHIO.

ROTARY VALVE.

Application filed March 17, 1922. Serial No. 544,503.

To all whom it may concern:

Be it known that I, CHARLES J. BERTHEL, a citizen of the United States, residing at Canton, in the county of Stark and State of Ohio, have invented certain new and useful Improvements in Rotary Valves, of which the following is a specification.

This invention relates to internal combustion motors, and has for one of its objects to provide a device of this character of improved construction and increased simplicity, and efficiency.

Another object of the invention is to provide a device of this character including a combined cylinder and valve which may be inserted or removed without disturbing the piston and other parts.

Another object of the invention is to provide a device of this character constructed without spring controlled valves, and therefore operates practically noiseless.

With these and other objects in view the invention consists in certain novel features of construction as hereinafter shown and described and then specifically pointed out in the claims, and in the drawings illustrative of the preferred embodiment of the invention.

Figure 1 is a vertical sectional elevation of the improved motor with the piston at the upper end of its stroke.

Fig. 2 is a similar view with the cylinder at the down or lower end of the stroke.

Fig. 3 is a transverse section on the line 3—3 of Fig. 1.

Fig. 4 is a transverse section on the line 4—4 of Fig. 2.

Fig. 5 is a vertical section of the combined cylinder and reciprocating valve in section on the line 5—5 of Figure 3, looking in the direction of the arrow above the figure, and

Fig. 6 is a similar view looking in the direction of the arrow below the Fig. 3.

Fig. 7 is an enlarged sectional detail illustrating the manner of supplying the lubricant to the moving parts.

The improved motor comprises an enclosing shell or casing 10 having an encircling cooling water space or chamber 11, and extended at one end to form the crank case, a portion of which is shown at 12, and with an annular seat 13 at the upper end. A head member, represented as a whole at 14, bears upon the upper end of the shell and

over the seat 13, thus forming a closure to the seat.

The head member 14 contains the usual spark plug represented conventionally at 15.

Disposed within the shell and fitting the same gas tight, is a combined rotative valve and piston 16, extending at the upper end into a cavity within the head member 14 and with an encircling rib 17 engaging in the channel 13. By this means the member 16 is rotatively suspended within the shell 10, and may be removed therefrom or deposited therein when the head member 14 is removed.

Formed in the inner wall of member 16 and at diametrically opposite points are guide channels, each consisting of a portion 18 extending in parallel relation to the longitudinal axis of the member 16 and a portion 19 directed obliquely to the longitudinal axis of the member 16.

The upper ends of the longitudinally directed portions 18 of the guide channels open through the upper end of the cylinder valve, to enable the piston and its rollers to be inserted and removed.

The piston of the improved motor is represented as a whole at 20 and includes an intermediate transverse partition or diaphragm 21 whereby an explosion chamber 22 is produced and with bearings 23 for the connecting rod of the motor.

Mounted on the piston near its upper end at diametrically opposite points are rollers 24 operating constantly in the guide channels 18—19.

The intake for the explosive gas is located at 25 near the upper part of the shell 10, while the exhaust port 26 is located intermediate the shell, preferably diametrically opposite to the intake port 25.

The combined valve and cylinder member 23 is provided with an intake port 27 and an exhaust 28 at different points circumferentially and likewise at different points longitudinally of the member 16, so that when the member 16 is disposed in one position the intake port 26 of the shell 10 will register with the intake port 27 of the valve member, and when the member 16 is disposed in another position the exhaust port 28 of the valve member will register with the exhaust port 26 of the shell.

The guide channels 18—19 are so arranged

and proportioned, that when the piston is at the upper end of its stroke, or located as shown in Fig. 1, the rollers 24 will be in the upper or longitudinally directed portions 18 of the guide channels and will dispose the port 27 in registering relation to the intake port 25 and likewise dispose the discharge port 28 of the member 16 spaced from the exhaust port 26 or with the exhaust "cut off".

By this arrangement while the piston is moving through the first part of its up or compression stroke the rollers 24 travel in the short oblique portions 19 of the guide channels and quickly rotate the valve 16 and cut off the intake 25 and the exhaust 26.

During the remainder of the compression stroke the rollers 24 travel in the longitudinal portions 18 of the guide channels 20 and hold both parts closed to enable the piston to produce the requisite compression of the gas in the cylinder. At the first part of the down or power stroke the explosion occurs, and the rollers 24 traveling 25 in the horizontal portion 18 of the guide channels hold the sleeve valve stationary with the intake and exhaust both cut off. During this portion of the stroke the expansion occurs and the piston is forced 30 downwardly.

When the rollers 24 reach the inclined or oblique portions 19 of the guide channels, the sleeve valve is suddenly rotated to register the exhaust ports 26—28 and 28', during 35 the time the rollers are in the oblique portions of the channels, and at the same time open the intake to permit a fresh charge of gas to enter the cylinder. The period of time during which the exhaust is open is so 40 short and the oscillation of the valve so rapid, that the inflow of fresh gas does not affect the action. At the first part of the return stroke, or while the rollers 24 are passing upwardly through the oblique portions 19 of the guide channels, the intake and exhaust are 45 closed, and the continued movement of the piston again compresses the gas and the explosion takes place at the end of the compression stroke, and the operation is repeated.

The piston 20 is provided with the usual packing rings 29, as shown.

Formed through the head member 14 is an oil duct 30 leading to the upper face of the 55 rib 17 to convey the lubricant to the member 16 and with a branch duct 30 communicating with an opening at the upper end of the channels 18, to convey the lubricant to the piston and the valve. Each side of 60 the motor may be provided with a set of the oil ducts, if required.

The improved device is simple in construction, can be inexpensively manufactured and of any size required, and contain-

ing few parts, and all the moving parts can 65 be "machined" at small expense to render the joints gas tight.

The preferred embodiment of the invention is disclosed in the drawings and set forth in the specification, but it will be understood that modifications within the scope of the claimed invention may be made in the construction without departing from the principle of the invention or sacrificing any 75 of its advantages.

Having thus described the invention what is claimed as new is:—

1. In an internal combustion motor, a cylindrical shell having intake and exhaust ports spaced longitudinally of the shell a 80 distance equal to the stroke of the piston, a cylindrical valve mounted for oscillation within the shell and having ports which register respectively with said intake and exhaust ports when the valve is in one position, said valve having inwardly opening 85 guide channels with the major portion of each channel extending longitudinally of the valve and communicating minor portions extending obliquely to the major portions, a piston within the valve and movable longitudinally of the shell and its valve and held from turning therein, and with a port registerable with the exhaust port when the piston is in its lower position, and projections carried by the piston and constantly engaging in the guide channels, whereby the movement of the piston operates to hold the valve from oscillation during the major part of its stroke and rotates it during the minor 90 part of its stroke.

2. In an internal combustion motor, a cylindrical shell having intake and exhaust ports spaced longitudinally of the shell a 105 distance equal to the stroke of the piston, a cylindrical valve mounted for oscillation within the shell and having ports which register respectively with said intake and exhaust ports when the valve is in one position, a piston within the valve and movable longitudinally of the shell and its valve and held from turning therein and with a port registerable with the exhaust port when the piston is in its lower position, and means 110 operative by the movement of the piston for oscillating the valve in one direction at the commencement of the compression stroke to hold the intake and exhaust ports closed during the compression stroke and the major portion of the power stroke and oscillating the valve in the other direction as the piston approaches the terminal of the power stroke, to rapidly open and close the intake and exhaust ports.

In testimony, whereof, I affix my signature hereto.

CHARLES J. BERTHEL.
